NURSING UNIT

Adda M. Allen, Arlington, Va., assignor to Disposable Bottle Corporation, Washington, D. C., a corporation of Delaware

Application March 14, 1944, Serial No. 526,354

3 Claims. (Cl. 215—11)

1

This invention relates to nursing units, and has for one of its objects the production of a simple and efficient nursing unit, one element of which comprises a replaceable throw-away, transparent or semi-transparent, semi-rigid container, which may be compressed by the fingers of an operator to stimulate the flow of the liquid out from the container and through the nipple which nipple also forms a part of the nursing unit and which compression will prevent the collapse of the nipple while an infant is nursing.

A further object of this invention is the production of a simple and efficient nursing unit comprising a replaceable throw-away content-visible, semi-rigid container, having a rigid shape-retaining and container-attaching neck, to which neck is secured a flexible nursing nipple of a conventional type, to provide a sanitary compact and easily assembled nursing unit, the container of which may be thrown away after each feeding and replaced by a new sanitary replaceable container.

Other objects and advantages of the present invention will appear throughout the following specification and claims.

In the drawings:

Figure 1 is a side elevational view of the nursing unit gripped by the hand of an operator;

Figure 2 is a longitudinal vertical sectional view of the nursing unit, a portion of the shape-retaining neck being shown in elevation;

Figure 3 is a bottom plan view of the body portion of the neck;

Figure 4 is a top plan view of the clamping ring of the neck;

Figure 5 is an enlarged vertical sectional view of a modified form of the container and neck-attaching means;

Figure 6 is an enlarged sectional view of the structure shown in Figure 5, with the parts shown separated;

Figure 7 is a side elevational view of the nursing unit, illustrating a heating blanket attached to the container, the nipple being shown in dotted lines;

Figure 8 is a bottom plan view of the structure shown in Figure 7;

Figure 9 is an enlarged vertical sectional view of a further modified form of the container and neck-attaching means.

By referring to the drawings, it will be seen that 10 designates the sterile content-visible, semi-rigid throw-away or disposable container preferably formed of relatively heavy Cellophane or like material or treated paper, or similar sub-

2

stance, having a glycerine base or other base, and sufficiently sturdy to retain its shape while at the same time permitting the container to be compressed by squeezing the fingers together in the manner shown in Figure 1. This action will stimulate the flow of liquid from the container 10, and at the same time prevent the collapse of the nipple 11 which is attached to the rigid shape-retaining neck 12. The container 10 is preferably provided with a suitable scale 13 to facilitate the measurement of the amount of fluid within the container 10. This container 10 is preferably transparent or semi-transparent to provide a content-visible container, so that the amount of the content remaining in the container or consumed by the infant may be easily determined at any time. Since the contents of the container are visible, the person tending the infant, by observing bubbles arising from the base of the nipple, will determine whether or not the contents are being consumed. This container 10 may be of any shape or size, but it is preferably of the wide-mouth type which is slightly larger than the bottom or base. This will facilitate nesting as the containers are packed for the trade.

The rigid shape-retaining neck 12 is preferably formed of rigid transparent or semi-transparent plastic of any suitable type and this neck 12 preferably tapers toward its outer end and terminates in a nipple-retaining bead or flange 15 over which the flexible nipple 11, of any suitable type, may be fitted. The neck 12 is provided with a depending skirt 16 at its lower end opposite the bead 15, as shown in Figure 1. An annular flange 17 is formed upon the neck 12 near its lower end and terminates in a depending collar 18, a portion of the inner face of which is internally threaded to receive an externally threaded clamping ring 19. This clamping ring 19 is provided with a laterally extending annular knurled flange 20 which extends flush with the outer face of the depending collar 18 and facilitates the threading of the ring 19 within the neck 12. The outer face of the depending collar 18 is preferably knurled adjacent the lower edge thereof, as shown. The neck 12 is provided with a pocket 21, in which the retaining flange 14 fits and is clamped in position by the ring 19, as shown in Figure 2. The under face of the pocket 21 and the upper face of the ring 19 are provided with a complementary rib and channel or tongue and groove bead structure to firmly grip the flange 14 and to lock and seal the joint between the neck 12, the ring 19, and the container 10. It should be noted that the

skirt 16 fits against the inner face of the container 10 and into the open mouth of the container. The open end of the container is clamped between the skirt 16 and the ring 19, and the flange 14 is clamped between the neck 12 and the ring 19.

As shown in Figure 5, a rubber or other resilient sealing washer or gasket 22 may be placed between the neck 12^a and the flange 14^a of the container 10^a. A clamping ring 19^a firmly clamps the flange 14^a against the washer or gasket 22. As shown in Figure 6, the neck 12^b may be provided with a sealing rib or tongue 23 and the flange 14^b of the container 10^b may be provided with a channel or groove 24 to receive the rib 23. A rib 25 may be formed upon the under face of the flange 14^b to fit into a channel 26 formed in the upper face of the clamping ring 19^b. It should be understood that the rib 25 and channel 24 may be pre-formed in the flange 14^b, as shown in Figure 6, or may be formed in the flange 14 only when the ring 19 is threaded into clamping engagement with the flange 14, as shown in Figure 2, without departing from the spirit of the invention.

As shown in Figure 9, the neck 12^c may be provided with a pocket for receiving the flange 14^c of the container 10^c, which pocket is provided with an inclined inner face 26. The ring 19^c is provided with a companion inclined face 27. The ring 19^c is threaded into the neck 12^c and is adapted to force the flange 14^c inwardly of the inclined faces and into a tightly clamped and sealing position. This will tend to crowd the semi-rigid material from which the container is constructed up into the corner 28 and prevent leakage of liquid from the container 10^c out from between the neck 12^c and ring 19^c.

In Figures 7 and 8, I have illustrated an electrically heated bottle warmer 29, preferably of a flexible blanket type, in which the container 10 may be mounted. The warmer 29 is preferably provided with a view opening 30 formed by the spaced side edges of the warmer, which is so located as to permit an operator to view the scale 13. The warmer 29 is preferably held tightly around the container 10 by means of the lacing cord 31, which spans the opening 30 and interlaces with suitable hooks or other means 32. Any suitable type of warmer may be used without departing from the spirit of the invention.

From the foregoing description, it will be noted that a very simple and efficient nursing unit has been produced comprising a semi-rigid and compressible content-visible receptacle, a rigid shape-retaining neck which is attached to the receptacle or container 10, and a flexible nursing nipple of any suitable type or design which is attached to the neck. The neck is preferably formed of rigid transparent material of any suitable type such as transparent plastic and this neck comprises a retaining ring which clamps the open mouth of the semi-rigid content-visible receptacle or container in engagement with the neck so as to assist in retaining the receptacle or container in its proper shape while at the same time permitting the body of the container to be slightly compressed by the fingers of an operator to stimulate the flow of liquid or fluid through the neck and through the nipple which is attached to the neck. An efficient means has been provided for attaching the semi-rigid replaceable container or receptacle in engagement with the neck and to seal

the junction of the container and the neck so as to prevent accidental flow of liquid through said joint. Furthermore, an efficient heating means may be used in conjunction with the unit to maintain the nursing formula at a proper or desired temperature, and this heating means is so formed as to be readily removable and to permit the content of the receptacle or container to be viewed at all times.

It should be understood that certain details in the construction of the nursing unit may be employed without departing from the spirit of the invention, so long as such changes fall within the scope of the appended claims.

Having described the invention, what is claimed is:

1. A nursing unit comprising a reusable collar and nipple, and a disposable container body made of pliant material capable of being pressed inwardly by hand to aid the nursing operation, said container having substantially straight side walls, a closed bottom and an open top end for removable attachment to said collar, said collar comprising a neck portion having a top central opening with means around said opening for the removable attachment of said nipple, said neck portion having a short depending skirt around which the material of the open top end of said container is wrapped and an annular sealing groove adjacent the upper end of said skirt into which the material of the open top end of the container is bent to be sealed therein, said neck portion having a threaded section thereon and said collar further comprising a narrow annular clamping ring of such diameter as to pass upwardly over and around said container from the closed bottom end thereof and to be disposed around the outside of the open top end of said container, leaving the body thereof exposed to be grasped by the hand and compressed as necessary during the nursing operation, said clamping ring being adjustably attached to said neck portion by cooperating threads and having a sealing surface which is presented to the material of the open top end of said container in said groove and which presses said material into sealing engagement with said skirt when said ring is adjusted on said neck portion.
2. A nursing unit comprising a reusable collar and nipple, and a disposable container body made of pliant material capable of being pressed inwardly by hand to aid the nursing operation, said container having substantially straight side walls, a closed bottom and an open top end for removable attachment to said collar, said collar comprising a neck portion having a top central opening with means around said opening for the removable attachment of said nipple, said neck portion having a short depending skirt around which the material of the open top end of said container is wrapped and an annular sealing groove adjacent the upper end of said skirt into which the material of the open top end of the container is bent to be sealed therein, said neck portion having a short depending outer flange spaced from said skirt with screw threads on the inner wall thereof, said collar further comprising a narrow annular clamping ring of such diameter as to pass upwardly over and around said container from the closed bottom end thereof and to be disposed around the outside of the open top end of said container leaving the body thereof exposed to be grasped by the hand and compressed as necessary during the nursing operation, said

clamping ring being adapted to enter the annular space between said skirt and said outer flange and being adjustably attached to said neck portion by threads on its outer wall which engage the threads on said outer flange, said clamping ring having a sealing surface which is presented to the material of the open top end of said container in said groove and which presses said material into sealing engagement with said skirt when said ring is adjusted on said neck portion.

3. A nursing unit comprising a reusable collar and nipple, and a disposable container body made of pliant material capable of being pressed inwardly by hand to aid the nursing operation, said container having substantially straight side walls, a closed bottom and an open top end for removable attachment to said collar, said collar comprising a neck portion having a top central opening with means around said opening for the removable attachment of said nipple, said neck portion having a short depending skirt around which the material of the open top end of said container is wrapped and an annular sealing groove adjacent the upper end of said skirt into which the material of the open top end of the container is bent to be sealed therein, said neck portion having a threaded section thereon and said collar further comprising a narrow annular clamping ring of such diameter as to pass upwardly over and around said container from the closed bottom end thereof and to be disposed around the outside of the open top end of said container, leaving the body thereof exposed to be grasped by the hand and compressed as necessary during the nursing operation, said clamping ring being adjustably attached to said neck portion by cooperating threads and having a sealing surface which is presented to the material of the open top end of said container in said groove and which presses

said material into sealing engagement with said skirt when said ring is adjusted on said neck portion, and an annular sealing gasket in said groove adapted to be compressed by said clamping ring to secure the seal of the material of the top open end of said container in said groove.
